UNITED STATES PATENT OFFICE

LULA H. ROBINSON, OF DALLAS, TEXAS

SCROLL AND LINE INDICATOR

Application filed March 23, 1929. Serial No. 349,460.

This invention relates to typewriter's equipment and it has particular reference to a stenographer's continuous note pad, and the principal object of the invention resides in the provision of a convenient device designed to save time and effort in typing manuscripts and notes.

Another object of the invention resides in the provision of a device capable of use not only as a holding means for a continuous note pad but can be used as a writing surface when it is desired to make notes in shorthand, or the like, for typing, in the absence of suitable desk space.

Still another object of the invention is manifest in the provision of a device embodying all the elements required in typewriter's copy holding equipment, yet simplifying the structure to such an extent as to eliminate a considerable amount of the equipment heretofore required for such use.

The invention further comprehends among its objects a compact method of keeping stenographer's notes which, by the ordinary methods, are usually prepared in the conventional note books and as will become apparent presently, the present invention provides a means whereby the notes can be made on a continuous roll which when filled, can be filed for future reference and since many more notes can be taken in this manner consuming a less amount of paper, a great saving in this commodity can be realized.

Having thus set forth the novel objects and salient features of the invention, a further description may be had by reference to the appended drawings, in which:

Figure 1 is an elevational view of the invention showing the paper rolls and gearing.

Figure 2 is a sectional view of the uppermost roll, taken on line 2-2 of Figure 1.

Figure 3 is a sectional view of the second roll, taken on line 3-3 of Figure 1.

Figure 4 is a cross-sectional fragmentary view taken on line 4-4 of Figure 1.

Figure 5 is a side elevational view, showing portions cut away to show gearing and tape reel on the topmost roll.

Figure 6 is a cross-sectional view taken

on line 6-6 of Figure 1 showing the tape roll, tension rollers and operating means.

Figure 7 is a view showing the particular type of split shaft used in this invention.

Figure 8 is a cross-sectional view taken on line 8-8 of Figure 1.

The common method used by stenographers in taking shorthand notes, being in the form of a note book, are often misplaced when not in use. This method is unsatisfactory and the method of supplying continuous rolls of paper for this purpose is considered a marked improvement in stenographer's equipment as the notes are retained in compact form for ready use at all times until the roll is completely used when the same can be neatly stored for future reference.

Moreover, the present invention comprehends a compact arrangement of parts calculated to provide a device capable of being produced at a minimum cost yet combining features that will make for maximum usefulness and efficiency.

Proceeding more in detail, reference is again made to the drawings in which 1 designates the roll upon which the paper is originally placed to be wound upon roll 2, as notes are made upon the paper 3 wound upon said said rolls.

It is, of course, the primary object of the invention, as stated, to move the paper at intervals from one roll to the other to present an exposed area 4, upon which notes are made, and to do so, means in the form of a projection 5 is provided operating longitudinally of the pad in a channel 6, which has connection to a roller 7 by means of a tape 8 of a predetermined length. It will become apparent presently how the paper is moved from the roll 1 to the roll 2 as the projection 5 is actuated.

In Figure 7 is illustrated the preferred form of shaft 9 upon which each of the rollers 1 and 2 are mounted. This shaft, as apparent in Figure 7, is split and one portion thereof is formed of a resilient material and bent outwardly in order to bind the end thereof and prevent free rotative movement of the roller except when required.

As apparent in Figure 2, a sectional view

of the roller 1 and its associated elements, the shaft 9 has one end nonrotatably inserted into a stub shaft 10, the latter, having integral therewith a clutch element 11. Co-operating with a clutch element 12 fixed to the roller 7, in which roller is contained a convolute spring 13. Affixed to the other end of this shaft 10, is a knob 14 arranged to operate the shaft longitudinally to bring the two clutch elements into operative or inoperative positions. It is understood that inoperative position of the clutch elements 11 and 12 allows the paper to be rolled from the roller 2 upon the roller 1 and when these clutch elements are engaged the reverse action takes place, that is to say, when one side of the paper has been used and it is desired to use the opposite side.

The character 9 has been used to indicate the shaft upon which the roller 2 is mounted, as well as to designate the shaft upon which the roller 1 is carried, there being no difference in construction.

It is understood that when the projection 5 is brought to the lowest point in the channel 6, the action likewise brings the paper off the roller 1, sufficient distance to cover the area 4, in view of the fact that the tape 8, under tension, bears upon the roller 14a mounted on a shaft 15 which carries the small gear 16, which latter enmeshes a larger gear 17, integral with the stub shaft 18 into the end of which is inserted the square end of the shaft 9 carrying the roller 2. A small spring 19, as apparent in Figures 1 and 4, is provided to maintain unmeshed condition of the clutch elements 20 and 21 carried by the shaft 15, but as tension is brought upon the roller 14 by the tape 8, the action is to urge the clutch elements into engagement against the action of the said spring 19, which action obviously causes rotation of the small gear 16 against the gear 17 to rotate the roll 2 in a counter-clock-wise direction, causing the paper 22 to move upward across the area 4 over the lateral roller 23 at the lower end of the plates 24 and 25, as it is moved off the roller 1, moving in a counter clock-wise direction by the return movement of the projection 5 in the channel 6, as provided for by the clock spring 13.

Returning to Figure 2, it is pointed out that a compression spring 26 is provided which applies a constant urge against a ferrule 27, the latter being adapted to hold the clutch element 12 operatively engaged with the element 11, but this action is not required except when it is desired to use the opposite side of the paper, by turning the plates 24 and 25 to the position shown in Figure 5. In the latter position, the gears 16 and 17 are rendered inoperative and the knob 14 is pulled outward to move the shaft 10 longitudinally to bring into engagement the clutch elements 11 and 12, which action transfers the

power of rotation from roller 2 to roller 1, thereby causing the paper to unwind from roll 2 and wind upon roll 1.

The operation of the clutch elements 11 and 12 has been briefly explained in the foregoing and to clarify this function, it is pointed out that the stub shaft 10, which carries the clutch element 11 is not only rotatable but is capable of endwise movement, which movement is obtained by pushing and pulling the knob 14, fixed to its extended end. When the shaft 10 is moved, the clutch element 11 is also moved and the latter is normally free to rotate independently of the companion clutch element 12. The clutch element 12, as apparent in Figure 2 is connected to or a part of the bushing or ferrule 27, surrounding the shaft 10 and which ferrule is freely mounted upon the shaft. The spring 26 normally bears upon the clutch element 12 so that when the shaft 10 is moved to bring the clutch element 11 into engagement with the clutch element 12, the spring 26 will offer yielding resistance of the element 12 with respect to the element 11. It is understood however, that the clutch elements are not moved into engagement except when it is desired to reverse the movement of the paper so that the other side thereof may be used. When this is done, the device has the appearance as shown in Figure 5.

In reversing the direction of travel of the paper as described in the foregoing, the position of roller 1 and plate 25 remains unaltered, but the plate 24 carrying roller 2, is turned under, as apparent in Figure 5, the ends of the two plates, 24 and 25, being pivotally joined links 28, as apparent in Figures 5 and 6. As a precaution against displacement of the paper as it is rolled upon the roller 2, a small parallel roller 29 is provided therebelow, its ends being journaled in the end bearings 30, supporting the roller 2, the latter being an integral part of the plate 24.

In mounting the two rollers, 1 and 2, the sleeves 31 are moved upon the stub shaft 32 against the resistance of spring 33 to allow the end of split shaft 9 to be aligned with the end of the stub shaft 32, whereupon the sleeve 31 is released allowing it to receive the end of the roller shaft 9. This sleeve is constrained against other than longitudinal movement by the slot and pin combination shown.

In operation, it is understood that the writing material travels off the roll 1, over roller 23 and across the surface or writing area 4 and onto roller 2, when the projection 5 is moved the full limit of the slot 6. This action causes both the rollers 1 and 2 to move in a counter-clockwise direction. The clutch elements 11 and 12 are normally inoperative when the writing material is being moved in the manner before stated, consequently while the tape moves the roller 7 in a clockwise di-

rection, such movement has no effect upon the movement of the roller 1. This operation continues until all of the writing material has been transferred from the roller 1 to the roller 2, whereupon the plate 24 is swung to the position shown in Figure 5 in dotted lines.

Reversal of the plates 24 and 25 as shown in Figure 5 allows the paper to be transferred from the roll 2 back upon the roll 1, allowing the blank side of the writing material to be exposed as it passes over the upper surface of the plate 25 onto the roller 1. In the first use of the pad the writing matter, as the writing material passes onto the roll 2 is concealed, thus it is apparent, in the second use of the pad that the writing matter will be against the surface of the plate 25 as it is transferred to the roll 1 by the actuation of the projection 5, which actuation is the same as in the preceding instance. It is apparent therefore that it is simply required to change the position of the plates as shown in Figure 6 to that shown in dotted lines in Figure 5, and connecting the loose end of the web of writing material to the roller 1, whereupon the pad is in a position for use.

Obviously, the structure shown is capable of considerable modification, and such modification as is considered in keeping with the appended claims is also considered within the spirit and intent of the invention.

I claim:

1. A scroll mounting including a pair of hinged plates each having roller receiving means on its free end, said rollers being arranged to receive a strip of writing material interwound thereon to travel over the upper surface of each of said plates when one of said rollers is rotated, means to successively rotate said rollers a predetermined distance in one direction and means to reverse said plates to expose the opposite side of said writing material.

2. A roll device including a pair of plates hinged at one end, each having means at their opposite ends to receive rollers arranged for carrying writing material, the latter being constrained to travel over the upper surface of each of said plates when said rollers are actuated, means for actuating said rollers, and means for reversing said plates to expose the opposite side of said writing material.

3. A roll device including a pair of plates hinged together at one end, one of which plates is of greater length than the other, rollers mounted upon the free end of each of said plates, whose axes are normally parallel and arranged to receive writing material, means for transferring said writing material from one of said rollers to the other, means for turning one of said plates under the other and clutch means associated with one of said rollers to change the direction of rotation

thereof to reverse the direction of travel of said writing material.

4. A roll device including parallel rollers arranged to carry a roll of writing material whereby the latter may be moved over a flat surface from one roller to the other, said flat surface being comprised of a pair of plates hinged together at one end and having means at their opposite ends for supporting said rollers, means for rotating one of said rollers to expose a predetermined area of said writing material and means for reversing the position of one of said plates to change the position of one of said rollers whereby to expose the opposite side of said writing material.

5. A scroll mounting including rollers arranged normally in parallel relationship to carry writing material for transfer from one roll to another over a plane surface, said plane surface comprising a pair of hinged plates having means thereon for independently supporting said rollers and means to change the position of said plates to expose the opposite side of said writing material.

In testimony whereof I affix my signature.
